TIRE

Richard F. Ward, Birmingham, Mich., assignor to
Chrysler Corporation, Highland Park, Mich., a corpo-
ration of Delaware

Filed Jan. 2, 1963, Ser. No. 73,029

Term of patent 7 years

(Cl. D90—20)

FIG. 1 is a front elevational view of a tire, showing my new design;

FIG. 2 is a perspective view on an enlarged scale of a portion of the tire; and

FIG. 3 is a fragmentary sectional view taken on the line 3—3 of FIG. 2.

The drawing is shaded to indicate contrasting areas.
The portions of the tire not shown are conventional.

I claim:

The ornamental design for a tire, substantially as shown and described.
